UNITED STATES PATENT OFFICE.

JAMES J. RAE, OF CHERRY VALLEY, MASSACHUSETTS, ASSIGNOR OF
ONE-HALF TO CHANNING SMITH, OF CHERRY VALLEY, MASSA-
CHUSETTS.

CARDING-MACHINE.

No. 810,171.

Specification of Letters Patent.

Patented Jan. 16, 1906.

Application filed February 10, 1905. Serial No. 245,020.

To all whom it may concern:

Be it known that I, JAMES J. RAE, a citizen of the United States, residing at Cherry Valley, in the county of Worcester and State of 5 Massachusetts, have invented certain new and useful Improvements in Carding-Machines, of which the following is a specification.

My invention relates to improvements in 10 carding-machines or machines for carding wool, cotton, &c., and more particularly to the "workers" and "strippers," so termed, combined with the main cylinder.

The object of my invention is to improve 15 upon the construction of a carding-machine as now ordinarily made, and particularly the arrangement of the workers and strippers relatively to the main cylinder and their combination therewith.

20 In my improved construction of a carding-machine I combine with the main cylinder the worker-rolls, preferably ten in number, arranged in pairs around the main cylinder and each worker-roll in engagement 25 with the main cylinder, but none of the worker-rolls in engagement with each other. I also combine with the main cylinder the stripper-rolls, preferably five in number, and each stripper-roll located between each pair 30 of worker-rolls and in engagement with each of said worker-rolls and also in engagement with the main cylinder.

35 By means of my improvements the wool or other material to be carded passes from the main cylinder onto one worker-roll of a pair and from said worker-roll onto a stripper-roll and from the stripper-roll onto the main cylinder, and at the same time the material from the other worker-roll of a pair 40 of worker-rolls located on the other side of the stripper-roll which has passed onto said worker-roll from the main cylinder also passes onto the stripper-roll, making two thicknesses of material on the stripper-roll 45 to mix the material, and then both thicknesses of material pass onto the main cylinder, and this operation is repeated and takes place in connection with every worker-roll around the main cylinder and every stripper- 50 roll. There is one-half the number of stripper-rolls as there are worker-rolls, and each stripper-roll is located between and in engagement with a pair of worker-rolls.

Referring to the drawings, Figure 1 is a

sectional end view of parts of a carding-machine embodying my improvements, and Fig. 2 shows a part of the main cylinder and a pair of worker-rolls and a stripper-roll detached and the material to be carded thereon.

In the accompanying drawings, 1 is the frame; 2, a stand thereon; 3, bearings for the central shaft 4 of the main card-cylinder 5, having cards comprising wire teeth 5' around its periphery.

65 6 represents the feed-rolls between which the material 7 to be carded passes onto the "licker-in" roll 8 and to the "tumbler" roll 9 and from said roll 9 to the main cylinder 5. On the opposite side of the main cylinder 5 is what is termed a "fancy" roll 10 and a "doffer" roll 11 on a shaft 12, mounted in 70 bearings 13 on the frame 1.

All of the above-mentioned parts may be 75 of the ordinary and well-known construction and operated in the usual way in carding-machines.

I will now describe my improvements.

Arranged around the main cylinder 5 are 80 the rolls 14, termed "workers," preferably ten in number and arranged in pairs, and each worker-roll is in engagement with the main cylinder 5; but none of the worker-rolls are in engagement with each other. Also arranged around the main cylinder 5 are the 85 smaller rolls 15, termed "strippers," preferably five in number. Each stripper-roll 15 is located between a pair of worker-rolls 14 and is in engagement with each one of the pair and also in engagement with the main 90 cylinder 5. The worker-rolls 14 are all rotated at a uniform speed in one direction opposite to the direction of rotation of the main cylinder, in this instance by means of a driving-belt 16, passing around driving- 95 rolls 17. The stripper-rolls 15 may be driven in any usual way in the same direction as the worker-rolls 14.

In Fig. 2 is shown how the material 7 passes from the main cylinder 5 onto each 100 of a pair of worker-rolls 14 and from one of the worker-rolls 14 onto the stripper-roll 15 and also from the other worker-roll 14 onto the stripper-roll 15 to make two thicknesses 105 and mix the material, and then from the stripper-roll 15 the material passes onto the main cylinder 5. This operation is repeated, and the same operation takes place with

each pair of worker-rolls and the stripper-roll between them, so that there is double carding and double mixing and very satisfactory results are obtained.

5 It will be understood that the details of construction of my improvements may be varied, if desired.

Having thus described my invention, what I claim as new, and desire to secure by Letters Patent, is—

1. In a carding-machine, the combination with the main cylinder, of the worker-rolls arranged in pairs, each one of a pair in engagement with the main cylinder, and the stripper-rolls, a stripper-roll for each pair of worker-rolls, and in engagement with each one of the pair, and also in engagement with the main cylinder, and means for rotating the workers and strippers in the same direction and opposite to the direction of rotation of the main cylinder, substantially as shown and described.

2. In a carding-machine, the combination with the main cylinder, of two worker-rolls in engagement therewith, and a stripper-roll in engagement with each of the worker-rolls,

and also in engagement with the main cylinder, and means for rotating the workers and the strippers in the same direction and opposite to the direction of rotation of the main cylinder, substantially as shown and described.

3. In a carding-machine, the main cylinder, a worker-roll in engagement therewith and adapted to receive the material therefrom, a second worker-roll in engagement with the main cylinder, and adapted to receive the material therefrom, a stripper-roll in engagement with both worker-rolls, and adapted to receive the material therefrom, and also in engagement with the main cylinder, and adapted to transfer the material from both worker-rolls onto the main cylinder, and means for rotating the workers and strippers in the same direction and opposite to the direction of rotation of the main cylinder, substantially as shown and described.

JAMES J. RAE.
